UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER BOX AND THE LIKE.

Application filed April 13, 1925. Serial No. 22,810.

This invention relates to improvements in paper boxes, having particular reference to boxes or cartons adapted to contain food products, as cereals, pastries, etc.

5 The objects attained in the improved box consist in a box which can be produced at low cost, which can be shipped and stocked in bulk knocked-down, and which is provided with means for effectively closing the 10 box after the same has been opened to remove a portion of the contents and thus to preserve the remaining portion against immediate deterioration which results with food products distributed in the common 15 type of boxes in which no provision is made to effectively close the boxes after the same have been once opened.

The importance of closing boxes in which cereal, pastry, fruit, and various other foods 20 are distributed is obvious and does not require emphasis other than mention of the fact that many food products of this character are packed in hermetically sealed containers, variously-shaped boxes and cartons, 25 thus to insure complete sanitation and normal wholesomeness or freshness of the product in the handling and stocking of the same incident to distribution.

Upon opening of the container by the consumer, however, this safeguard provided by 30 the manufacturer is in most part destroyed, so far as it relates to the portion of the content remaining in the container after the initial portion has been removed, seventy-five to ninety percent of the food, in case of 35 the average consumer, being thus subjected to more or less unhygienic deterioration in the open or ineffectually closed containers.

To overcome or minimize this serious fault, 40 certain well-known food products, as Quaker Oats for example, are distributed in round boxes provided with a tight-fitting cover or lid adapted to be replaced on the boxes after each removal of the content, and thus to preserve the food down to the last portion remaining in the box in a state approximating 45 normal wholesomeness.

The round box type of container, however, is more costly than the common type 50 of sealed carton, and is not well adapted for handling in bulk for the reason that the boxes do not lend themselves to knocked-down form; also, the round box runs greatly

into bulk in packing and stocking because of the waste space between boxes which adds as 55 much as fifty percent to the bulk or space over that required for square or rectangular-shaped boxes for a like amount of product. For the correction of these difficulties, to cheapen cost in production and handling, 60 and at the same time to preserve food products so distributed, my invention provides a rectangular-shaped box, adapted to be knocked-down, to be hermetically sealed, if desired, and provided with a specially constructed lid or cover cap which serves to reseal the box in effect after each opening thereof.

In the accompanying drawings:

Fig. 1 illustrates the blank from which the 70 main portion of the box is formed;

Fig. 2 illustrates the blank from which the lid portion of the box is formed;

Fig. 3 is a longitudinal sectional view of the box as shaped into a container with the 75 lid applied;

Fig. 4 is an elevation of the box closed and illustrating, by dotted outline, the application of an outer hermetical wrapper;

Figs. 5 and 6 respectively illustrate the 80 body and lid portions of the box in knocked-down form.

As here shown, the main portion of the box consists of side portions 1, 2, 3 and 4, 85 part 1 being joined to part 4 by means of an adhesive strip 5. The bottom of the box, as set on end, consists of end flaps 6, 7, 8 and 9 adapted to be folded one upon another and glued in a manner well known in common practice.

The top end of the box is made special, 90 consisting of short yieldable cover-sealing strips 10, 11, 12 and 13 which act to stiffen the end of the box and aid materially in effecting a tight-fitting relation of the lid 95 to the box after the seals have been broken. It will be obvious, however, that normally tight-fitting of the lid will result irrespective of the sealing strips.

The lid or cover of the box consists of a top portion 14, side portions 15—16 and opposite end portions 17, 18, and 19, the latter portions being adapted to be folded one over another and glued together. The side portions 15—16 in a preferred form of the lid are provided with sealing tabs 20 which

are adapted to be glued to the body of the box, as illustrated in Fig. 4, the tabs being adapted to be severed from the lid on perforated or scored lines 21 to remove the lid upon first opening of the box.

As illustrated in Fig. 4 the boxes as used for food products are preferably hermetically sealed by an outer wrapper, as indicated by the dotted outline around the box, 10 the lid sealing flaps 20 being inside the wrapper.

The advantages of the improved box will be obvious from the illustrations and the foregoing detailed description. It will be 15 seen that the box is simple and cheap to make, that it lends itself admirably to quantity production and to handling and shipping in bulk both in knocked-down form as furnished to the manufacturer and as filled 20 with food products to be distributed to the consumer. The peculiar construction and manner of applying the lid to the box, having particular reference to the yieldable sealing strips 10, 11, 12 and 13 which tend 25 to flare outwardly with their free edges engaging the adjacent sides of the lid and thus to effect a close-fitting relation of the lid on the box, tend to make a close-fitting cover for the box,—the outer sealing tabs 20 serving 30 to hold the lid securely in place when

the boxes are filled until the seals are broken upon first opening of the box.

The improved box, as herein shown, is designed for production on special automatic machinery which makes possible a 35 large reduction in production cost of the boxes.

Having described my invention, I claim:

1. A rectangular shaped box adapted to having an open end, a lid for the box adapted to be placed telescopically over said end and having depending flaps on opposite sides thereof adapted to be secured adhesively to the adjacent sides of the box and an outer wrapper for sealing the box 45 hermetically.

2. A rectangular shaped box having an open end, a lid for the box adapted to be placed telescopically over said end and having depending flaps on opposite sides thereof, secured to said sides on lines defined by scorings or perforations coinciding with the lower edges of the lid, and adapted to be secured adhesively to the adjacent sides 50 of the box whereby to secure the lid on the box and to adapt the lid for convenient removal by severing the tabs on said lines. 55

In testimony whereof, I affix my signature.

SAMUEL BERGSTEIN.
